UNITED STATES PATENT OFFICE.

HERBERT V. HARDMAN, OF BELLEVILLE, NEW JERSEY, ASSIGNOR TO RUBBER-BOUND
BRUSH COMPANY, OF BELLEVILLE, NEW JERSEY, A CORPORATION OF NEW JERSEY.

BRUSH.

No. 925,178.

Specification of Letters Patent.

Patented June 15, 1909.

Application filed December 7, 1908. Serial No. 466,343.

To all whom it may concern:

Be it known that I, HERBERT V. HARDMAN, a citizen of the United States of America, residing at Belleville, in the county of 5 Essex and State of New Jersey, have invented certain new and useful Improvements in Brushes, of which the following is a specification, reference being had therein to the accompanying drawing.

10 This invention relates to brushes adapted to be manipulated by hand, and more particularly to shaving brushes, although its application and use might be given a much wider range.

15 My object is to greatly cheapen the whole structure, especially the handle, and also to reduce the weight of the latter as much as possible.

20 A further object of my invention is to provide a superior fastening device for the bristles or hair to prevent them from dropping or being pulled out or becoming loosened, and to allow the brush-portion to be more readily and positively and securely 25 attached to the handle-portion or to be removed therefrom for repairs, cleaning, inspection, or the substitution of a new brush-portion when necessary.

To this end my invention consists in the 30 peculiar features and combinations of parts more fully described hereinafter and pointed out in the claims.

In the accompanying drawings, Figure 1 35 represents a longitudinal section of my complete invention as applied to an ordinary shaving brush, and Fig. 2, a similar view showing the handle and brush-portion separated.

The reference numeral 1 indicates a brush 40 handle composed preferably of gutta percha or hard rubber which material is desirable because it is light, and impervious to water, and takes a fine polish, and possesses many other obvious advantages for an article of 45 this kind. This handle is hollow, being blown out in the usual manner, and is formed integral with a socket-portion 2 in which the peculiarly bound end of a brush 3 is removably secured. Across the middle of the 50 socket-portion 2 is an integral, transverse, circular web which constitutes an abutting shoulder 4 against which the bound end of the brush abuts when screwed into the socket. The upper ends of the bristles of 55 the brush 3 are first grouped and stuck

together by soft plastic rubber 5 and are then forced through and surrounded by a binding ring 6, preferably composed of pewter or lead and having a conical interior wall 7 converging as it extends downward or outward to form a contracting or smaller opening at the outside than at the inside of the ring. This construction results in producing a key-stone or dovetail anchorage or fastening for the bristles after the soft rubber 5 hardens within the ring, and any longitudinal strain on the brush will tend to bring a tighter grip, both collectively and individually, on the bristles to prevent them from coming out. The bound end of the brush is squared off smoothly to meet a corresponding smooth, flat surface upon the under side of the transverse circular shoulder 4 for the purpose of effecting a tight joint 8 between these two parts. The outside of 60 the binding ring lies parallel to the axis of the ring or at right-angles to the end of the brush in order to facilitate the operation of screwing and unscrewing the brush from the socket, and to make the work of manufacturing easier. In this cylindrical exterior surface are formed annular screw threads 9 which engage corresponding threads 10 on the annular interior side-wall of the socket-portion 2.

Among the advantages of this construction 65 might be mentioned the fact that the bristles at the point of fastening are bound together by a water-proof cement which is not easily made soluble by hot water or soap suds, and that the brush-portion can be made and secured in the socket by simply screwing it in place. The lead binding band which screws 70 into the gutta-percha socket will not corrode and bind these two parts together, but will be unaffected by water or soap, and can always be unscrewed with facility. Furthermore, as the binding ring or band 6 is composed of lead and the screw threads thereon being cut 75 in contradistinction to being spun, they effect a much tighter and better joint when screwed in place. The inside or thinner edge of the binding band is squared off flush with the end of the bristles, and when the brush is 80 screwed home a grinding joint is effected against the shoulder 4, which joint together with that formed by the screw threads at the side, produce a tight seal which excludes water.

It is evident that my invention might be 85

changed in many ways that would naturally suggest themselves to a skilled mechanic; therefore I do not limit myself to the exact construction herein shown, but consider myself entitled to all the variations that come within the scope and spirit of my device.

Having thus described my invention, what I claim is:

1. In a brush of the character described, a hollow handle-portion provided with a transverse circular shoulder substantially closing its lower end, in combination with a socket-portion having a cylindrical threaded interior wall, and a brush provided with an exteriorly threaded binding ring and a squared end, whereby the brush is adapted to screw into said socket and to abut tightly against said shoulder.

2. In a brush of the character described, the combination with a hollow handle-portion provided with a transverse circular shoulder substantially closing its lower portion, of a socket portion containing a cylindrical wall threaded to receive a corresponding member, a brush bound with a cylindrical binding ring, exterior threads thereon adapted to take into those of the socket, a conical interior wall in said ring, and plastic water-proof cement for holding the bristles within the ring.

In testimony whereof I affix my signature in presence of two witnesses.

HERBERT V. HARDMAN.
